UNITED STATES PATENT OFFICE.

FRANZ FR. BÜRGER, OF MANNHEIM, GERMANY, ASSIGNOR, BY MESNE ASSIGNMENTS, TO HEINRICH LANZ, AKTIENGESELLSCHAFT, OF MANNHEIM, BADEN, GERMANY, A CORPORATION OF GERMANY.

WASTE-HEAT BOILER.

Application filed November 4, 1924, Serial No. 747,720, and in Germany December 24, 1923.

This invention relates to a waste heat boiler with superheater; and the object thereof is to provide for boilers of this type a superheater which is simple in construction, efficient in operation, and capable of control so as to avoid the danger of overheating the steam.

In internally-fired steam boilers means have heretofore been employed for directing the flue gases as they leave the tube system of the boiler either directly into the stack or entirely through a superheater or in part only through the superheater and the remainder into the stack. Since in such an arrangement the flue gases are so cooled down in their passage through the boiler that comparatively little heat is left for thereafter superheating the steam, any partial by-passing of the flue gases around the superheater is only an evil, rendered necessary in order either to increase their velocity or to provide sufficient heat for the feed-water heaters located in the stack.

In waste heat boilers, on the other hand, the conditions are exactly reversed. The heat here available is not so great as is the case in internally-fired boilers, and hence, if the superheater were placed behind the boiler, it would be impossible to obtain any superheat of the steam whatever. Consequently, with boilers of this type, it is customary to place the superheater ahead or in front of the boiler,—as regards the circulation of the waste gases,—so that the gases will pass through it before entering the boiler. The superheater being thus exposed to exceedingly high temperatures, the aim,—directly the opposite to that in the case of an internally-fired boiler—is to so keep down the superheat of the steam as to minimize the danger in overheating.

This problem has heretofore been solved simply by cooling down the overheated steam in the outer air, by mingling with it some saturated steam from the boiler, or by conducting it through a coil located in the lower and hence coolest part of the boiler. The first mentioned expedient however entails a considerable loss of heat, the second requires special piping and an expensive and complicated manual control by means of valves, and the third renders any control during operation practically impossible.

A waste heat boiler with superheater is also known in which the waste gases are introduced into the boiler through a conduit having two branches leading one through the superheater and the other directly to the boiler, and control devices located in these branch passes make it possible to conduct a part only of the gases through the superheater and the remainder to the boiler. This apparatus is also objectionable, in the first place, because the control of the superheat is imperfect, secondly, because the high heat of the waste gases is not properly utilized when a part thereof is conducted directly to the boiler, and, finally, because it is not possible to pass the waste gases and the steam in counter-current through the superheater.

I have obviated all of the above-mentioned defects by my present invention which consists, briefly stated, in employing with waste heat boilers a front superheater of a construction similar to that of the rear or smoke-box superheater used with internally-fired boilers and in reversing the circulation of the furnace gases therethrough, thus making it possible with a damper-control to avoid the overheating of the steam without loss of heat and without expensive and complicated mechanism.

The invention is illustrated in the accompanying drawings, in which—

Figure 1 is a view, in vertical longitudinal section, of a waste heat boiler and superheater, embodying my improvements; Fig. 2 is a view of the same, in transverse section; Fig. 3 is a view, in transverse section, of a modified form of the superheater in which the waste gases are introduced thereto from below; and Fig. 4 is a view similar to Fig. 3 but showing two of the control dampers in a different position.

Referring first to Figs. 1 and 2, 1 is the boiler and 2 is a cylindrical wall or shell which at its rear end is attached to the head of the boiler and forms an extension thereof. This extension drum is closed at its outer end by a head wall 5 equipped with a door 5¹ which is removably secured therein by turn-buckles or the like and is provided with an opening or inlet passage 4 for the introduction of the waste gases. An inner cylindrical wall 6, which is preferably rigidly attached to the inner face of the door

5¹, extends from end to end of the drum extension and divides the interior thereof into a central flue communicating at one end with the inlet opening 4 and at the other end with the interior of the boiler and a surrounding annular chamber within which is placed the superheater 3, comprising two semicircular banks of coils with connecting headers, preferably mounted upon the walls 10 of the outer drum. A transverse wall 7, fixed within this cylindrical inner wall, substantially midway its length, has formed therein a centrally-located opening 8 in which is mounted a damper 9, operable from 15 outside the drum to open and close the opening. The cylindrical inner walls is further provided at its outer end, between the end door and the transverse wall, with a bottom opening 10, which is controlled by the two 20 dampers 10¹ and 10² mounted therein and operable from outside the casing, and at its inner end, between the transverse wall and the boiler, with a top opening 11 which is controlled by two corresponding dampers 25 11¹ and 11² similarly mounted and operated.

The operation of the boiler and superheater is as follows: To start the boiler, that is to say, when the boiler is cold and there is no steam in the superheater, the 30 dampers 10¹ 10² and 11¹ and 11² are closed and the damper 9 is opened, so that the waste gases from the furnace will be drawn into the boiler through the central flue in the superheater. As soon as sufficient steam 35 has been generated to fill the superheater coils, the dampers 10¹ 10² and 11¹ 11² are opened, whereupon some of the hot gases will pass into and through the superheater chamber, and, finally, the damper 9 is closed 40 thereby causing all of the gases to pass through the superheater chamber. If the heat of the waste gases is so high as to overheat the steam, as will frequently be the case, the temperature of the steam can be 45 readily be controlled—for example, by closing one of the two dampers in each of the openings 10 and 11 and by opening the damper 9 more or less. Although the waste gases will now pass through one side only of 50 the superheater chamber, the temperature of the steam in the two coils will be equalized at the headers.

In the modification shown in Figs. 3 and 4 the waste gases are introduced into the 55 superheater from below through the flue pipe 12 and are conducted thence to the boiler either through the central passage formed by the cylindrical inner wall 13 or through the surrounding superheater chamber formed between this inner wall and the casing 2. The inner cylinder is preferably secured, as before, to the inner face of a solid door removably mounted in the outer head of the superheater casing; but here both the 60 upper opening 14, controlled by the dampers 65

14¹ and 14², and the lower opening 15 controlled by the dampers 15¹ and 15², extend throughout the entire length of the wall, the latter dampers serving either to close the opening 15 or on swinging downwardly to 70 connect this opening with the inlet pipe 12 and shut off the inlet pipe from the superheater chamber.

This form of superheater is controlled in operation substantially as before. On starting the boiler the dampers are set, as shown in Fig. 3, to close the opening 14 and to connect the opening 15 with the inlet pipe 12, thus directing the furnace gases directly to the boiler through the central passage. 80 Then, as steam is generated, the dampers are adjusted so as either to close the openings 14 and 15 and thereby force all of the furnace gases through the superheater chamber or, as shown in Fig. 4, to close one side 85 of each opening, thus directing a part of the gases through one side only of the superheater chamber and by-passing the remainder through the central passage.

What I claim as new, and desire to secure 90 by Letters Patent, is—

1. The combination with a waste heat boiler of a steam superheater which is set in front of the boiler and comprises an outer casing through which all the waste gases 95 employed to heat the boiler are passed, an inner cylindrical wall extending from end to end of the casing and dividing its interior into an inner and surrounding outer chamber, two semi-circularly disposed superheater coils mounted within the outer chamber on opposite sides of the inner wall, and means comprising damper-controlled openings for passing the waste gasses from an inlet to an outlet opening in the casing either 100 directly through the inner chamber or to the extent desired through either or both sides of the outer chamber.

2. The combination with a waste heat boiler of a steam superheater which is set 110 ahead of the boiler and comprises an outer casing with the inlet opening for the admission thereto of all the furnace gases employed to heat the boiler and an outlet opening connecting with the interior of the boiler, a cylindrical inner wall extending from the front to the rear of the casing and at the rear encircling the outlet opening therefrom and dividing the interior of the casing into a central inner and surrounding outer chamber, two semi-circular banks of superheater coils mounted within the outer chamber on the opposite sides thereof, and damper-controlled openings associated with the inner wall arranged and controllable to connect the inlet with the outlet opening either 115 wholly through the central inner chamber or to close such connection to the extent desired and open the connection for the passage of varying quantities of the furnace 120

gases through either or both sides of the annular chamber containing the superheater coils.

3. A steam superheater comprising, in combination, a casing adapted to be attached at one end to a boiler in communication with the gas-circulating system thereof, an inner cylindrical wall which extends from end to end of the casing encircling the opening to the boiler and dividing the interior thereof into an inner central and surrounding outer chamber and which is provided with a top and bottom opening, two semi-circular banks of superheater coils mounted within the outer chamber on opposite sides thereof and of the openings in the inner wall, an inlet opening in the casing opposite one of the openings in the inner wall, and a pair of dampers each operable to close either one-half of the said inner opening or the connection between the outer casing opening and one side of the outer superheater chamber.

4. A steam superheater comprising, in

combination, a cylindrical casing adapted to be attached at one end to the front of a waste heat boiler in communication with the gas-circulating system thereof, an inner cylindrical wall which extends from end to end of the casing encircling the outlet opening to the boiler and dividing the interior thereof into concentric inner and annular outer chambers and which has top and bottom damper-controlled openings extending substantially the length thereof, two semi-circular banks of superheater coils mounted within the outer chamber on opposite sides thereof and of the openings in the inner wall, and an inlet opening in the bottom of the casing registering with the bottom opening in the inner wall, the bottom opening in the inner wall being controlled by a pair of dampers each operable to close either one-half of said opening or the connection between the said inlet opening and one side of the outer chamber.
